UNITED STATES PATENT OFFICE

WILLIS D. RICH, OF HINGHAM, MASSACHUSETTS

CONVERTIBLE FURNITURE

Application filed July 17, 1928. Serial No. 298,418.

The invention relates to convertible furniture of a type essentially adapted for schoolroom use by which the normal seating capacity of a schoolroom may be increased and the room be used for assembly purposes.

In a schoolroom the chairs with accompanying desks are ordinarily arranged with aisles between them. The object of the invention is to provide these chairs with convertible desk members or attachments which allow the desks to be eliminated as occasion may require and the desk members or attachments converted into chairs for filling the aisles between the permanent chairs. The further object of the invention is to simplify and strengthen the entire structure, arrange for easy convertibility of the convertible parts and for a positive setting of these parts when converted, and otherwise make the construction as efficient and practical as possible.

The invention can best be seen and understood by reference to the drawings, in which—

Figure 1 is a side elevation of one of the permanent chairs and combined with it the mounting for the convertible attachment later to be referred to.

Fig. 2 is a side elevation the same as Fig. 1 with the convertible attachment applied to its mounting to form a desk.

Fig. 3 is a vertical section of the parts shown in Fig. 1.

Fig. 4 is a vertical section of the parts shown in Fig. 2.

Fig. 5 is a section on the line 5—5 of Fig. 7 showing the convertible attachment applied to its mounting to form an aisle chair.

Fig. 6 is a view mainly in vertical section showing one of the permanent chairs, the mounting combined with it for supporting the convertible attachment and said attachment together with the seat of the permanent chair turned to an out-of-the-way or stacked position.

Fig. 7 shows in front elevation permanent chairs and associated therewith the convertible attachment converted to form an aisle chair.

Fig. 8 is a plan of the structure shown in Fig. 1.

Fig. 9 is a view mainly in plan but partly in section showing the base portions or pedestals of certain of the permanent chairs and connecting therewith frames which assist in the support of the mounting for the convertible attachments.

Fig. 10 is a view in perspective of one of the permanent chairs removed from its supporting pedestal.

Fig. 11 is a perspective of the convertible attachment.

Fig. 12 is a view partly in side elevation and partly in vertical section of the chair with modified structure, and

Fig. 13 is a view in perspective of certain of the modified parts entering into the structure shown in Fig. 12.

It will first be explained that the structure embodying the invention comprises a permanent chair and combined therewith a convertible attachment comprising a desk and its support. There is also combined with the permanent chair a mounting for the convertible attachment. This mounting in one embodiment of the invention, as will later be explained, acts as a support for the back of the permanent chair. Normally the attachment which comprises the desk and its support, is mounted to hang over the back of the permanent chair, the desk itself then being turned to a position where it may be used by a person sitting behind the permanent chair and fronting the desk. When, however, it is desired to fill the aisle alongside the permanent chair and between it and the next adjacent permanent chair on the other side of the aisle, then the desk and its support are lifted off their mounting and mounted to hang between two adjacent permanent chairs, filling the aisle, the desk support then forming the back of the aisle chair and the desk then being turned down to form the seat of the aisle chair. Reference to the general construction is thus made at this point for the purpose of obtaining a clear understanding of the parts now to be referred to.

The permanent chair designed to be fastened securely to the floor, comprises a base or pedestal 1. Set into this base and rising vertically from it is a standard 2. This

55

60

65

70

75

80

85

90

95

100

standard is adjustable vertically with relation to the base and is fixed to it in any adjusted position by means of a pin or set screw 3 passed through the side of the base and engaging the standard as by entering a slot 4 therein. (See Fig. 12.) Carried by the standard 2 and fixed to the top thereof by a fastening 5 is a seating board or block 6 horizontally arranged, which acts as a support or rest for the seat of the chair when turned down into its operative position. 7 represents the seat of the chair. Parallelly arranged and connected respectively to the opposite ends of the seating block 6 are side rails 8. These side rails extend back horizontally from the seating block and thence are turned to have an upward extension with preferably a slight backward inclination. Connected to the upwardly-extending portions of these side rails are cross-bars 9 which co-operate with the side rails to which they are fastened to form the back of the chair. The cross-bars are secured to the side rails in any suitable manner and are preferably arranged one at the extreme top end of the side rails and the other below the upper cross-bar in spaced relation thereto leaving below it a clear or open space to the rear edge of the seating block 6. The seat 7 is arranged with in this space and is secured to turn pivotally upon the horizontally-extending portions of the side rails 8 back of the seating block 6 by means of trunnions 10 arranged on the under side of the seat forward of the rear edge thereof and turning on and between the side rails as aforesaid. Thus arranged the seat may have an upturned out-of-the-way position against the back of the chair as shown in Fig. 10 or it may have a down-turned operative position, then resting upon the seating block 6. The side rails 8 or rather those portions which function as a frame for the back of the chair are preferably of angle iron, the ends of the cross pieces 9 fitting into the angle formed by the iron and securely fixed in place. The lower portions of the side rails, however, are made as flat bars, one flange of the iron being cut away, and it is these flattened portions of the rails that are secured to the opposite ends of the seating block 6 and between which also the seat is pivoted, the arrangement being such that the seat may be turned freely between them. One flange at the lower end of the angular portion of the side rails is preferably turned inward to form stops 12 against which the top rear end of the seat is adapted to bear when the seat is in its down-turned operative position, the rear end of the seat turning away from these stops when the seat is raised into its upturned out-of-the-way position.

Associated with each of the permanent chairs is a mounting for the desk and its support comprising the convertible attachment

as aforesaid. This mounting comprises uprights 15 adapted to be fixed to the floor one at either side adjacent the back of the permanent chair. The uprights apart from their fastening to the floor are rigidly supported by means of a frame 16. This frame, horizontally arranged, extends between the two uprights and is rigidly fastened to them by bolting or otherwise. Thence the frame extends beneath the seat of the permanent chair and is provided, centrally disposed within its forward edge, with a collar 17 which slips over the top end of the base or pedestal of the permanent chair and is securely fixed to it by means of a tightening screw 17' which fastens through the rim of the collar into the top of the base or pedestal. This frame gives great rigidity to the uprights holding them securely in place. It will also be observed that the frame occupies an out-of-the-way position with relation to the seat of the permanent chair inasmuch as it extends within a plane lying well below the seat of the permanent chair or one substantially flush with the top of the base or pedestal on which the permanent chair is mounted.

The uprights 15 are standardized in that they are alike in form and size. They rise vertically to a height preferably a little below the top to the back of the permanent chair with which the uprights are associated. The uprights are provided with vertical groovings forming ways in their opposite sides. These groovings as a matter of expediency are made alike for the opposite sides of each standard although for purposes of description they will be referred to as ways on the inner and outer sides of the uprights. The inner sides of the uprights will be considered those sides facing the back of the permanent chair to which they are adjacent while the outer sides of the uprights will be considered the sides which face an aisle alongside the permanent chair. The inner sides of the uprights are provided with vertical ways 18 and 19, respectively, while the outer sides of the uprights are provided with vertical ways 18' and 19' respectively. The vertical ways 18 and 18' occupy positions adjacent the rear edge of the uprights and these ways are preferably approximately true vertical ways not appreciably inclined. The ways 19 and 19' occupy positions adjacent the forward edge of the uprights and while vertical are slightly inclined in a rearward direction. Each of the uprights is provided along its front edge with a forward-projecting bracket 20. These brackets, owing to the spacing of the uprights to which they are secured, with relation to a permanent chair with which the uprights are associated, will extend outwardly by the sides of the permanent chair and provide supports for the seat of the aisle chair, as will later be referred to. Each of the uprights along its front edge just

above its bracket 20 is provided with a down-turned projecting keeper 22 and a socket 23 formed back of this keeper.

25 is the convertible attachment (see Fig. 11). The attachment comprises a desk 26 convertible into a chair seat and a support 27 for the desk convertible into a chair back. The desk 26 is generally rectangular in form. Its top surface, when the member is functioning as a desk, has the finish of a desk, while its under surface has the finish of a chair seat. The desk support 27 consists of a frame generally rectangular in form and has the general form of a chair back for when converted it functions as a chair back. It comprises spaced crossbars 28 and 29, respectively, with connecting bars 30 along the sides. When the desk member 26 is functioning as a desk the crossbar 28 forms a continuation of the outer end of the desk, the top of the crossbar being preferably provided with a rearward-extending portion 28'. In finish the top surface of the crossbar 28 is made to correspond with the top surface of the desk and the crossbar is preferably provided with sockets 31 for holding desk equipment. Fixed to the rear side of the desk support and lying beneath the rearward-extending portion 28' of the crossbar 28 are beveled blocks 32. These blocks provide rests against which bear brackets 33 fixed to the under side of the desk and assisting in the support of the desk. Fastened to the opposite sides of the desk support 29 are elongated strips or bars 34. In width the desk support is substantially equal to the space between the uprights 15 at the back of one of the permanent chairs, or to the aisle space between the spaced uprights of adjacent chairs. When occupying the space between the uprights at the back of one of the permanent chairs the mounting bars 34 of the desk support will be slidably contained to lie within the ways 18, 18 of the respective uprights, and when the support is occupying the aisle space between the spaced uprights of adjacent chairs the mounting bars 34 will be slidably contained to lie within the ways 19', 19' of the respective uprights.

40 The desk member 26 is pivotally connected to its supporting member 27 by a set of hinged connections, and these hinged connections will be described in the light of the member 26 when functioning as a desk and the member 27 then functioning to support the desk, all substantially as shown in Fig. 11. The hinged connections comprise hinges 35 fastened by strips 36 to the top surface of the desk adjacent the rear edge of the desk. Connecting, also, with the hinges 35 are straps 37 which extend over the top surface of the crossbar 28 and its extension 28' of the desk support lying within grooves 38 cut therein. The straps 37 connect with hinges 39 arranged at 45 the forward edge of the crossbar 28. Con-

necting, also, with the hinges 39 are strap extensions 40 which extend downward over the front face of the desk support and connect with hinges 41 located adjacent the bottom edge of the desk support. Connecting, also, with the hinges 41 are straps 42 fixed to the desk support adjacent its bottom edge. With the desk 26 thus hinged connected to its support 27, when the support is in an upright, substantially vertical position, the desk may either be maintained to occupy a substantially horizontal position with extension rearward of the top end of the support, or be turned over the support to occupy a substantially horizontal position with extension forward of and below the lower end of the support. When occupying its rearwardly-extending position as aforesaid the desk will extend in substantial rearward continuation of the crossbar 28 of the desk support or frame and its extension 28'.

When the desk support or frame is slidably contained within the ways 18, 18 of the uprights at the back of one of the permanent chairs it will be supported in adjusted position by means of pins 44 set into any one of the series of openings 45 formed within the uprights at the lower end portions of the ways, the bottom ends of the mounting bars 34 of the desk support engaging these pins. When the desk support or frame is slidably contained within the ways 19', 19' of the spaced uprights of adjacent chairs it will be supported in adjusted position by means of stops 46 in the respective ways, the bottom ends of the mounting bars 34 engaging these stops. The desk support is also equipped with the locking members 47 which assist in the support and maintenance of the desk as will presently be explained.

The operation is as follows: Normally, as for example in a schoolroom where desks are to be used in connection with permanent chairs with aisles running between the chairs, then the convertible attachment comprising the desk and its support is mounted on the uprights 15 at the back of a permanent chair. This mounting is effected by sliding the mounting bars 34 of the desk support into the ways 18, 18 of the respective uprights, entrance being had thereto from the top. The desk support will be moved down within the ways of the uprights to a position where the desk supported by it extending backward will lie in a position for use by one seated in another of the permanent chairs back of which the desk is hung. When thus positioned the attachment will be maintained in place by the bearing of the ends of the mounting bars 34 of the desk support or frame against the pins 44. The desk will then be supported by the hinged connection to the support or frame and also by the bearing of the brackets 33 on the desk against the blocks 32 on the support. Assisting also in the sup-

port of the desk are the locking members 47 on the desk which then extend inward beneath the rearward-extending portion 28' of the top crossbar of the desk support or frame (see Fig. 2). Thus the desk will be held securely in place.

When it is desired to fill the aisle between adjacent spaced permanent chairs, then the convertible attachment comprising the desk 10 and its support is lifted off the uprights on which it is mounted at the back of one of the permanent chairs and placed in the aisle where it is mounted upon the adjacent spaced uprights of adjacent ones of the permanent 15 chairs. This mounting is effected by sliding the mounting bars 34 of the desk support into the ways 19', 19' of the respective uprights with entrance from the top, and the bars are moved down in the ways until they engage the 20 stops 46 when the desk support becomes maintained in adjusted position. Thus arranged the desk support 27, now functioning as a chair back, remains securely in place and will be in substantial alignment with the backs of 25 the permanent chairs. With the desk support thus positioned the desk or member 26, through its hinged connection with the member 27, will then be turned over the top thereof, inverted and located in a position where it 30 will come to rest on the brackets 20, the desk 26 then functioning to form a seat for the aisle chair. When thus positioned the desk will be maintained against outward displacement by the locking members 47 on the desk, slipped in back of the keepers 22 on the respective uprights and entering the sockets 23 35 formed back of the keepers. In addition to preventing outward displacement of the desk when thus forming a seat for the aisle chair, the engagement between the locking members 40 47 on the desk and the keepers 22 on the uprights will act to prevent the entire convertible attachment 25 from being raised until the member or seat 26 has been turned up.

In order to prevent displacement of the aisle chair from the uprights on which it is mounted and to lock the chair to these uprights, each of the uprights is preferably provided with a strap 50 which extends across 45 its way 19' and when the mounting bars 34 of the member 27 are slipped downward into these ways they will lie back of the respective straps 50, thereby holding the member 27 and the entire aisle chair with it in place and 50 preventing its separation from the uprights upon which it is mounted.

A further capability of the structure resides in the fact that the convertible features are such as to permit of arrangement being 55 made to afford easy access for sweeping between and around the permanent chairs. In such case the aisles are cleared of the auxiliary chairs and the attachments mounted at the backs of the permanent chairs. The 60 seats of the permanent chairs are then turned

up. The convertible attachments are then lifted so that the desk member 26 of each may be turned over the back of a permanent chair and each assume a stacked position, substantially as shown in Fig. 6 which practically eliminates the seats and desks and provides easy access around the permanent chairs. 70

In connection with the further capabilities of the structure, attention is directed to the 75 frame 16. This frame apart from assisting in the support of the uprights, provides also a shelf beneath the seat of each of the permanent chairs which may be used by one sitting back of the chair. The frame or 80 shelf thus provided is spaced well below the seat of the permanent chair leaving a compartment between it and the seat sufficiently large to receive a box or cabinet of considerable size, or books and the like may be 85 placed within it as occasion may require.

In Figs. 12 and 13 there is shown a slight modification especially with relation to the backs of the permanent chairs. In the previous figures and especially in Fig. 10 the 90 back of the permanent chair is shown attached through the side rails 8 of the chair to the seating board or block 6 which acts as a support or rest for the seat of the chair when turned down into its operative position. 95 According to the modified construction a seating board or block 6' is provided on the upper end of the adjustable upright 2 on which the seat is mounted and the seat 7 is secured directly to this block by a hinged 100 connection 51, the seat then being capable of being turned up or down the same as before. Instead of providing a back for this seat of the permanent chair which is independent of the uprights as in the construction previously described, a back 52 is provided which is mounted upon the uprights. This back is made substantially like the desk-supporting member 27 which functions as a 105 back for the aisle chair as previously described. The back 52 comprises side bars 53 with connecting crossbars 54 and 55 respectively all combining to form a chair back. The back is mounted upon the uprights 110 by slipping its side bars 53 downward into 115 the ways 19, 19' on the inner sides or faces of the respective uprights, entrance being made from the top. The back is held in any adjusted position by set screws 56 passed through straps 57 which cross the ways 19, 19' and back of which the side bars 53 of the 120 back lie when slipped downward into the respective ways. These straps are similar to the straps which cross the ways 19', 19' on the exterior faces of the uprights as explained above. Thus arranged, the backs of the permanent chairs may be set in any 125 adjusted position, both the backs and the seats of the permanent chairs then being made adjustable.

Having thus fully described my invention, I claim and desire to secure by Letters Patent of the United States:—

1. The combination comprising adjacent spaced chairs, spaced uprights arranged at the backs of said chairs, brackets on said respective uprights, a removable attachment mounted upon and between the uprights at the back of one of said chairs and comprising a desk convertible into a chair seat, a support for the desk convertible into a chair back, and means connecting said desk and support whereby they may be converted as aforesaid, means for mounting said attachment upon and between the uprights at the back of said one of the chairs, and means whereby said attachment may be mounted upon and between adjacent spaced uprights of adjacent chairs to form an aisle chair between said chairs, the desk support then being converted to lie between said adjacent spaced uprights of said adjacent chairs to form the back of the aisle chair, and the desk being then converted to rest upon said brackets and form the seat of the aisle chair. 50
2. The combination comprising adjacent spaced chairs having spaced uprights arranged at the backs of said chairs, a removable attachment mounted upon and between the uprights at the back of one of said chairs and comprising a desk convertible into a chair seat, a support for the desk convertible into a chair back and means connecting said desk and support whereby they may be converted as aforesaid, means for mounting said attachment upon and between the uprights at the back of one of said chairs, means whereby said attachment may be mounted upon and between adjacent spaced uprights of adjacent chairs to form an aisle chair between them, the desk support being converted to form the back of the aisle chair and the desk being converted to form the seat thereof, means for supporting the desk when functioning as a seat for the aisle chair, and means forming an interlocking connection between the desk and said uprights when said desk is functioning as a seat for the aisle chair for preventing displacement of the desk. 50
3. The combination comprising adjacent spaced chairs having spaced uprights arranged at the backs of said chairs, each of said uprights having vertical ways open at the top ends thereof and formed on the interior and exterior sides of said uprights, a removable attachment comprising a desk convertible into a chair seat, a support for the desk convertible into a chair back, and means connecting said desk and support whereby they may be converted as aforesaid, said desk support being adaptable to be mounted upon the uprights at the back of one of said chairs or upon the adjacent spaced uprights of adjacent chairs and when thus mounted lie slidably contained within the ways on said up- 55
- rights, means for supporting the desk support when mounted between the uprights at the back of one of said chairs, and means for supporting said desk support when mounted to lie between adjacent spaced uprights of adjacent chairs. 70
4. A removable, convertible chair attachment comprising a desk member, a supporting member, means hingedly connecting the two members whereby the desk member may be turned from a substantially horizontal position rearwardly of and adjacent the upper end of said supporting member to a substantially horizontal position forwardly of and near the lower end of said supporting member, and brackets secured to the desk member and assisting in its support when occupying its rearwardly-extending position as aforesaid. 75
5. A removable, convertible chair attachment comprising a desk member, a supporting member, said supporting member including a frame having a top crossbar extending rearwardly thereof and blocks on the rear side of the frame arranged below the rearwardly-extending portion of said top bar, means hingedly connecting the two members whereby the desk member may be held in a position rearwardly of and in substantial horizontal extension of said top crossbar of the frame and be turned to occupy a substantially horizontal position forwardly of and near the lower end of the frame, and brackets secured to the desk member and bearing against said blocks when the desk member is occupying its rearwardly-extending position as aforesaid. 80
6. A removable, convertible chair attachment comprising a desk member, a supporting member, said supporting member including a frame having a top crossbar extending rearwardly thereof, means hingedly connecting the two members whereby the desk member may be held in a substantially horizontal position rearwardly of and in substantial extension of said top crossbar of the frame and be turned over the frame to occupy a substantially horizontal position forwardly of and near the lower end of the frame, means assisting in the support of the desk member when occupying its said rearwardly-extending position, and means secured to the desk member adapted to fit in beneath the said rearwardly-extending portion of said top crossbar when the desk member is occupying its rearward-extending position as aforesaid. 85
7. In a convertible chair attachment, a converting means comprising a plurality of strap members triple hingedly connected adapted to render a desk member and its support convertible into a chair seat and a chair back respectively. 105
8. In a convertible chair attachment, comprising separate members, one a desk member convertible into a chair seat and the other 120
- 130

a support for said desk member convertible into a chair back; a hinged conversion means comprising a member affixed to said desk member, a second member affixed to said support member, and a plurality of intermediate strap members hingedly connected to each other and to the aforesaid members.

9. The combination comprising adjacent spaced chairs, spaced uprights arranged at the backs of said chairs, a removable attachment mounted upon and between the uprights at the back of one of said chairs and comprising a desk convertible into a chair seat, a support for the desk convertible into a chair back, and means connecting said desk and support whereby they may be converted as aforesaid, means for mounting said attachment upon and between the uprights at the back of said one of the chairs, means whereby said desk support may be mounted upon adjacent spaced uprights of adjacent chairs to form the back of an aisle chair located between said adjacent spaced chairs and the desk then be converted to form the seat of the aisle chair, means for preventing said support when functioning as the back of the aisle chair from drawing away from the uprights upon which it is mounted, and means for supporting and retaining the desk when functioning as the seat of the aisle chair.

10. The combination comprising adjacent spaced chairs, spaced uprights arranged at the backs of said chairs, a removable attachment mounted upon and between the uprights at the back of one of said chairs and comprising a desk convertible into a chair seat, a support for the desk convertible into a chair back, and means connecting said desk and support whereby they may be converted as aforesaid, means for mounting said attachment upon and between the uprights at the back of said one of the chairs, means whereby said desk support may be mounted upon adjacent spaced uprights of adjacent chairs to form the back of an aisle chair located between said adjacent spaced chairs and the desk then be converted to form the seat of the aisle chair, means connected to said uprights for supporting the desk when functioning as the seat for the aisle chair, and means forming a releasable interlocking connection between the desk and said uprights when the desk is functioning as a seat for the aisle chair for preventing displacement of the desk.

11. The combination comprising adjacent spaced chairs, spaced uprights arranged at the backs of said chairs each of said uprights having vertical ways open at the top thereof and formed on the interior and exterior sides of said uprights, an attachment for said chairs comprising a desk convertible into a chair seat and a support for the desk convertible into a chair back, means hingedly connecting said desk and support whereby the desk may

be held in a position to function as a desk with extension rearward of said supporting member and be turned and held in a position to function as a chair seat with extension forward of said supporting member, said desk support being provided with means whereby it may be supported within the ways formed on the interior sides of the uprights at the back of one of said chairs or within the ways formed on the exterior sides of the uprights of adjacent chairs.

12. The combination comprising adjacent spaced chairs, spaced uprights arranged at the backs of said chairs, each of said uprights having vertical ways open at the top thereof and formed on the interior and exterior sides of said uprights, an attachment for said chairs comprising a desk convertible into a chair seat and a support for the desk convertible into a chair back, means hingedly connecting said desk and support whereby the desk may be held in a position to function as a desk with extension rearward of said supporting member and be turned and held in a position to function as a chair seat with extension forward of said supporting member, mounting bars on the opposite sides of the supporting member by which it may be slidably contained within the ways formed on the interior sides of said uprights at the back of one of said chairs or within the ways formed on the exterior sides of the uprights of adjacent chairs, and stops for said mounting bars contained within said respective sets of ways.

13. The combination comprising adjacent spaced chairs, spaced uprights arranged at the backs of said chairs, an attachment for said chairs comprising a desk convertible into a chair seat and a support for the desk convertible into a chair back, means hingedly connecting said desk and support whereby the desk may be held in a position to function as a desk with extension rearward of said supporting member or be turned and held in a position to function as a chair seat with extension forward of said supporting member, means for mounting said attachment on and between the uprights at the back of one of said chairs whereby said desk will have rearward extension as aforesaid, means for mounting said attachment between the spaced uprights of adjacent chairs whereby said desk will have forward extension as aforesaid, and means for supporting and retaining the desk when functioning as a chair seat including keepers on said uprights and locking members adapted and arranged to have interlocking engagement with said keepers.

14. The combination comprising adjacent spaced chairs, spaced uprights arranged at the backs of said chairs, an attachment for said chairs comprising a desk convertible into a chair seat and a support for the desk convertible into a chair back, means hingedly

connecting said desk and support whereby the desk may be held in a position to function as a desk with extension rearward of said supporting member or be turned and held in a position to function as a chair seat with extension forward of said supporting member, means for mounting said attachment on and between the uprights at the back of one of said chairs whereby said desk will have rearward extension as aforesaid, means for mounting said attachment between the spaced uprights of adjacent chairs whereby said desk will have forward extension as aforesaid, locking members on said desk adapted and arranged to have interlocking engagement with said support when said desk is occupying its rearward-extending position as aforesaid, and keepers on said uprights with which said locking members have interlocking engagement when said desk is occupying its forward-extending position as aforesaid.
